UNITED STATES PATENT OFFICE.

EWEN HENDERSON MITCHELL, OF BEDFORD, ENGLAND, ASSIGNOR OF ONE-THIRD TO
ALBERT EUSTACE SHORT AND ONE-THIRD TO HUGH OSWALD SHORT, BOTH OF
BEDFORD, ENGLAND.

AIRSHIP OF RIGID TYPE.

1,314,350.

Specification of Letters Patent. Patented Aug. 26, 1919.

Application filed April 23, 1919. Serial No. 292,074.

To all whom it may concern:

Be it known that I, EWEN HENDERSON MITCHELL, a subject of the King of Great Britain, residing at Bedford, Bedfordshire, England, have invented certain new and useful Improvements in Airships of Rigid Type, of which the following is a specification.

In balloons or airships of the rigid type, 10 that is comprising flexible gas containers supported within an inclosing rigid framework, the gas containers are located in such framework end to end and provision should be made in the event of one of the gas containers becoming accidentally deflated to take or support the end pressure of the adjacent gas containers. In known constructions such endway pressure has been taken by means of taut radial and cord wires extending in transverse planes between the gas containers and fixed to the surrounding framework, and, especially upon deflation, an abnormal strain is brought upon such transverse wires and upon the supporting framework.

Now the object of the present invention is to dispense with the use of such taut radial and cord wires between the ends of the gas containers and to support the endway pressure of the containers by means which shall not practically produce any distorting strains in the rigid framework, while at the same time maintaining the maximum of strength with the minimum of weight of the structure.

The invention will be described with reference to the accompanying diagrammatic drawings, in which Figure 1 is a diagrammatic longitudinal section of a portion of a rigid airship constructed according to this invention, and Fig. 2 is a transverse section showing a system of supporting wires between the ends of the gas containers.

In the longitudinal section at Fig. 1, three complete gas containers 1, 2 and 3 and a portion of a fourth marked 4 are shown, located within the usual rigid framework 5 of the airship.

The ends of the gas containers according to this invention are formed somewhat spherical, preferably as shown in the configuration of the lower end of a pear, that is with a depression or concavity about in the center of the end. In the drawing Fig.

1, the curves 6 of one end of the gas container 2 are convex, while the curves of the other end 7 are concave, the ends of one gas container fitting closely onto the ends of the next gas container.

Between the adjacent ends of the gas containers, supporting wires, such as 8, 9, Fig. 2, are arranged, the ends of the wires being secured to the rigid frames 10, and the wires are not strained taut as hitherto but pass loosely between the ends of the gas containers, so that the wires 8, 9 conform to the curves of the ends of the gas containers. Preferably this transverse system of loose wires 8, 9 may be supported at the center by a longitudinally extending wire 11 shown by a dot and dash line at Fig. 1 and also indicated at Fig. 2, this central line wire 11 extending through the gas containers. The curvature of the ends of the gas containers and the position of the transverse wires as indicated at Fig. 1 are therefore so arranged that there will be practically no distorting stresses on the framework.

Obviously with such a construction the loosely fitted transverse wires 8, 9 are not employed for the purpose of maintaining the rigid form of the structure, but assuming that the gas container 2 becomes deflated, then the adjacent end of the container 1, which was concave, will assume a convex form as shown by the dotted lines 12, Fig. 1, and be supported by the transverse wires 8, 9 located between the containers 1, 2, and further the container 1, for instance in assuming such convex curves, will be increased in cubical capacity with a corresponding reduction in the pressure of the gas contained therein. Owing to the shape of the ends of the gas containers the transverse wires 8, 9 may be of much less strength than those at present used, and moreover the strains on the main structure of the airship caused by one container becoming deflated, are reduced to a minimum and distorting stresses on the framework are obviated.

In the example of the invention illustrated in the drawings the gas containers in transverse section and the framework are of a form described in my copending application Serial No. 292,073, filed April 23, 1919, that is the gas containers are of approximately pear-shaped figure in transverse section and the outer rigid framework 5 con-

forms to such shape, and lift wires 13, Fig. 2, extend interiorly from the frames 14, 15 at the reentering angles to the corridor 16, the ends of the lift wires being fixed respectively to the said frames and to the corridor, and such lift wires pass through the gas containers.

What I claim as my invention and desire to secure by Letters Patent is:—

- 10 1. In airships or the like of rigid type; the combination with an outer rigid framework; of flexible gas containers located in the interior of same end to end, the ends of each gas container being of somewhat spherical 15 formation with an approximately central depression such as of the configuration of the lower end of a pear, the convex end of one gas container fitting into the adjacent concave end of the next gas container, and a 20 number of supporting wires extending in planes transversely of the longitudinal axis of the airship and having their ends secured to the rigid framework and passing between the curved ends of adjacent gas containers, 25 said supporting wires being of sufficient length to permit them to conform to the curves of the ends of the inflated gas containers between which they pass, and whereby when a gas container becomes deflated 30 the adjacent end of the next container which was concave will assume a convex form and be supported by said transverse wires.
2. In airships or the like of rigid type;

the combination with an outer rigid framework; of flexible gas containers located in the interior of same end to end, the ends of each gas container being of somewhat spherical formation with an approximately central depression such as of the configuration of the lower end of a pear, the convex end of one gas container fitting into the adjacent concave end of the next gas container, a number of supporting wires extending in planes transversely of the longitudinal axis of the airship and having their ends secured to the rigid framework and passing between the curved ends of adjacent gas containers, said supporting wires being of sufficient length to permit them to conform to the curves of the ends of the inflated gas containers between which they pass, and a longitudinal wire extending about centrally through the gas containers to which central wire said series of transversely extending supporting wires are connected, and whereby when a gas container becomes deflated the adjacent end of the next container which was concave will assume a convex form excepting at the central part where the supporting wires are held by the longitudinal wire.

In witness whereof I have hereunto set my hand in the presence of two witnesses.

EWEN HENDERSON MITCHELL.
